UNITED STATES PATENT OFFICE.

STEPHEN HIPKINS, OF MARTINS FERRY, OHIO.

JOINT FOR ARTICLES OF GLASSWARE.

SPECIFICATION forming part of Letters Patent No. 729,863, dated June 2, 1903.

Application filed February 16, 1903. Serial No. 143,600. (No model.)

To all whom it may concern:

Be it known that I, STEPHEN HIPKINS, a citizen of the United States, residing at Martins Ferry, in the county of Belmont and State of Ohio, have invented or discovered certain new and useful Improvements in Joints for Articles of Glassware, of which improvements the following is a specification.

My invention relates to an improvement in joints for articles of glassware and like material.

The object of my improvement is to obtain a firm and lasting joint.

In the manufacture of many glass articles and articles of similar material it is necessary or desirable to attach to the body of the article fittings or other parts which form part of the completed article. These fittings or other parts may themselves be formed of glass or like material, or they may be formed of any other material—for example, brass.

In the accompanying drawings, which form part of this specification, I have illustrated my improved joint applied to a glass lamp-body. To the lamp-body are joined fittings of metal and other parts of glass, and the union in each instance is effected by my improvement. I do not, however, limit myself to the particular application illustrated, for I consider my invention broadly applicable to articles of various materials and to articles designed for various uses.

In the accompanying drawings, Figure 1 is a view, partly in elevation and partly in section, of a lamp in which the several parts of the lamp itself are united by my improved joint and in which the fittings are attached by my improved joint. Fig. 2 is a view, in detail and on larger scale, of a portion of the lamp-body and collar detached. Fig. 3 is a view, in detail on the same scale as Fig. 2, of a portion of the lamp-bowl, a portion of the lamp-foot, and the joint-forming means, all detached.

Parts which are repeated in the several figures bear the same reference-numerals in every case.

In Fig. 1, 1 represents the bowl of the lamp, which (it will be assumed) is of glass. 2 represents a collar formed (it will be assumed) of brass, adapted to receive the lamp-burner, and this collar 2 is united to the lamp-body

by my improved joint. 3 represents a foot or base, which will also be assumed to be of glass, and this foot is united to the bowl 1 by 55 means of the joint which constitutes my invention.

My invention consists in a substantially circular flange or projection formed upon the exterior surface of the article, the diameter 60 of this projection being greater at some point than at another point nearer the surface of the article, and a corresponding metallic ferrule forming part of or affixed to the article or fitting to be applied and compressed into 65 binding contact with such projection or flange. In the drawings, 11 illustrates such a flange formed upon the exterior surface of the bowl of the lamp about the neck 12, to which the collar 2 is applied. This flange is preferably formed, as shown, with a portion of its outer surface that of a truncated cone tapering inward. Collar 2 is provided with a ferrule 21, adapted when the collar is applied to surround flange 11 and to be compressed into 70 binding contact with said flange. In Fig. 2 the parts are shown detached, and in Fig. 1 they are shown united. Another similar projection 11^a is formed on the lower side of the bowl 1 and upon its exterior surface, 75 and the foot 3 is provided with a ferrule 31, adapted to surround projection 11^a and to be compressed upon that projection to make binding contact therewith and join the bowl 80 of the lamp with its foot. As shown in Fig. 85 2, ferrule 21 forms part of collar 2, and, as shown in Fig. 3, ferrule 31 is a separate part which is attached to foot 3. This connection between ferrule 31 and foot 3 is in the drawings shown to be a screw-joint. Any known 90 form of joint may be employed, and it will be understood that my improved joint herein described may be employed to unite the ferrule and the foot 3 in like manner as it is shown and described to unite the ferrule and 95 the bowl 1. The preferred mode of compressing the ferrules upon the flanges or projections is by spinning the metal down to contact, a process well known in the art.

I have found it desirable in many instances 100 to form upon that portion of the surfaces of the article upon which the ferrules are spun lugs or projections 13. Recesses may be formed in the ferrule to engage these lugs, or

the metal of the ferrules may be spun over the lugs. This feature (illustrated in Figs. 1 and 2) prevents the parts joined together from turning one upon another. I have also 5 found it desirable in many instances to form upon the projections or flanges shoulders 14 14^a and to form upon the ferrules shoulders 24 34, adapted to be brought into opposition to shoulders 14 14^a when the ferrules are in 10 place and to so dispose the oppositely-placed shoulders that they will be drawn toward one another in the operation of spinning the ferrules in place. Between these oppositely-placed shoulders I introduce packing 4. This 15 packing is formed of plastic or elastic material and is compressed between the shoulders, as described. It may serve both to cushion the parts one upon another, as when placed between the bowl and foot of a lamp, and it 20 may serve to afford an impervious joint, as when placed between the bowl of a lamp and the collar. In such a place it not only relieves the upper parts of the lamp of jarring, but it also prevents the creeping of oil to the 25 outer surface of the bowl.

The chief advantages which are attributable to my invention are a firm joint, a durable joint, a joint which may be cushioned to relieve jars and blows, and a joint which 30 may be rendered impervious to water, oil, or gas.

I claim as my invention—

1. The combination of an article of glass or like material provided with a projection of tapering contour and of smaller diameter at the 35 base than at the free end, and a metallic ferrule having one end secured to said article by compression against the tapering surface of said projection, substantially as described.
2. The combination of an article of glass or 40

like material provided with a projection of tapering contour and of smaller diameter at the base than at the free end, and provided with a lug, and a metallic ferrule having one end secured to said article by contact with the 45 surfaces of said projection and lug, substantially as described.

3. The combination of an article of glass or like material having formed upon its surface a tapered projection of smaller diameter at 50 the base than at the free end, and having formed upon its surface a lug, and a metallic ferrule adapted to fit over said projection and having a recess adapted to engage said lug, substantially as described. 55

4. The combination of an article of glass or like material having formed upon its surface a shoulder and a tapered projection of smaller diameter at the base than at the free end, and a metallic ferrule provided with a shoulder 60 abutting against the said shoulder upon the article, the ferrule being secured to the article by a compression upon said tapered projection, substantially as described.

5. The combination of an article of glass or 65 like material having formed upon its surface a shoulder and a tapered flange of smaller diameter at the base than at the free end, a metallic ferrule having a shoulder and compressed upon said tapered flange, and a body 70 of packing material held between the shoulders formed upon the article and upon the ferrule, substantially as described.

In testimony whereof I have hereunto set my hand.

STEPHEN HIPKINS.
